SAFETY GUARD

Wilfrid H. Searjeant, Rochester, N. Y., assignor to
Taylor-Shantz Inc., Rochester, N. Y., a corpora-
tion of New York

Application November 16, 1938, Serial No. 240,773

6 Claims. (Cl. 74—615)

This invention relates to safety guards for presses, shears etc. and has for its principal object to provide a safety guard which will efficiently guard both small and large danger zones on machines having operating members with uniform or variable long movements, such as hydraulic presses, compressed air operated presses, toggle presses, percussion presses, shears etc.

A further object of this invention is to provide a safety guard which may be made to operate during any part of the movement of an operating member.

Another object of this invention is to provide a safety guard that will force the operator's hands or arms out of the danger zone in advance of the closing movement of the operating member and then form an efficient protective barrier during the closing movement.

All these and other objects and attendant advantages of this invention will become more clearly apparent from the detailed description thereof which follows, reference being had to the accompanying drawings in which

Figure 1 is a front elevation of a hydraulic press equipped with the safety guard.

Figure 2 is a vertical section taken on the line 2—2 in Figure 1.

Figure 3 is a horizontal section taken on the line 3—3 in Figure 1.

Figure 4 is a horizontal section taken on the line 4—4 in Figure 1.

Figure 5 is an enlarged front elevation of the safety guard and its actuating member.

Figure 6 is a horizontal section taken on the line 6—6 in Figure 5.

The safety guard, forming the subject matter of my present invention, is especially adapted for use on presses, shears etc. in which the operating member has a long and not too fast movement. Any form of press may have the guard attached thereto and for illustrative purposes I have shown and described it in connection with a hydraulic press in which a hydraulic ram 1 operates a movable bed 2 toward a stationary head 3 to subject the material to be operated upon to the pressure of the ram 1 thru suitable forming dies 4, 4. The press has the base 5 and on this base are supported the uprights 6, 6 which adjustably support the head 3 by means of the nuts 7, 7 and guide the bed 2 in its movement toward and away from the head. To prevent injury to the operator of the press he must remove his hands or have them forceably removed from between the dies on their closing movement or keep his hands

from entering between the dies during the closing movement thereof.

These protective functions are efficiently performed by my safety guard which comprises a number of pairs of levers 8, 8 which are pivoted together at the middle at 9, 9 and hinged to one another at the ends at 10, 10 to form an expandible and contractible gate-like structure as illustrated in Figure 5. The bottom end of one of the pair of levers 8 at the right hand end of the gate is pivotally mounted on the pivot stud 11 carried by the lower end of the supporting member or upright 12 and the upper end of the other of the pair of levers 8 at the right hand end of the gate is pivotally connected to the arm 13 which in turn is mounted to swing on the pivot stud 14 carried by the bracket 15. The latter is mounted on the side of the supporting member 12 so as to form a part thereof.

To operate the levers so as to have them extend in the manner illustrated in dotted lines in Figure 5, an extension arm 16 is attached to the lever end pivoted on the pivot stud 11 and the movement of this extension causes all of the levers to swing on their center pivots and force the hinged ends apart or bring them together to expand or contract the gate formed by them. The upper end of one and the lower end of the other of the pair of levers 8 at the free end of the gate have the guide blocks 17 and 18 pivoted thereon. Each of these blocks is grooved on the inside at 19 with a cover plate 20 held over the groove. The guard arm 21 extends thru these grooves and is normally clamped into the block 18 by its cover plate 20 to fixedly support it thereon while the guide block 17 is allowed to freely slide up and down on the guard arm. In this way the movement of the guide block 17 on the free moving end of the gate and the swinging arm 13 on the stationary end thereof permits the levers of the gate to move in unison. A stop pin 22, which projects from the supporting member, keeps the swinging arm 13 from swinging too far so that the return movement of the gate from its extended position will not be delayed or made difficult by the alignment of the pivotal connection between the arm 13 and the lever 8 with the center of rotation of this arm and lever.

The free end of the guard is guided and held rigid in a vertical plane by the guard arm 21. For this purpose this guard arm extends into the guide slot 23A provided between the guide rails 23, 23. These rails are supported at one end on the supporting member or upright 12 and at the other end by a similar supporting member 24.

The latter support may be dispensed with if the travel of the guard is short and the support at one end by the supporting member 12 is sufficient to hold the guide rails rigid. The guard arm 21 in its movement in the guide slot 23A thus guides the gate structure in a straight line movement and by its engagement with the sides of the guard rails assists in holding the gate structure rigid.

The guard arm is longer than the height of the gate structure and, as above pointed out, is adjustable in the guide block 18 so that it can be made to variably project below the gate structure in order to protect any danger area below the gate structure from which the hand or arm of the operator must be displaced on the operation of the guard. The guard arm is also adjusted so that its lower end extends below the top of the bed 2 and is located in front thereof. This keeps the guard arm and gate in a vertical plane in front of the bed and prevents it from being forced toward the dies.

For the operation of the guard the extension arm 16 carries the bracket 26 which is swiveled to the outer end thereof and is provided with a pair of parallel rollers 26A suitably spaced from each other. The cam rod 27 projects thru the bracket 26 between the rollers 26A and is moved up and down therein for the operation of the safety guard as will presently appear. The cam rod has a uniform, square cross section thruout its length and is bent to provide the angular cam 28 intermediate the ends thereof.

The cam rod is adjustably clamped in place in the bracket 29 which is attached to the moving table 2 of the press. For this purpose the free end of the bracket is provided with the channel 29A to have the cam rod slidably held in place therein by means of the cover plate 30. Set screws 31 in the side of the bracket are adapted to engage the cam rod and adjustably hold it fixed therein.

The cam section in the cam rod is so arranged that the upper straight section of the rod is thereby laterally offset from the lower straight section of the rod so that on the vertical movement of the cam rod the roller bracket is moved laterally and swings the arm 16 for the operation of the levers 8 of the guard. The movement of the upper straight section of the cam rod thru the roller bracket holds the arm 16 stationary in the position in which the gate structure of the guard is held contracted for the inoperative position of the guard. The movement of the angular cam section 28 of the cam rod thru the roller bracket causes the bracket to turn and be moved laterally to swing the arm 16 for the operation of the gate structure of the guard and the movement of the lower straight section of the cam rod thru the roller bracket keeps the arm 16 fixed with the guard in its operated position.

The cam rod can thus be adjusted in its supporting bracket to cause its cam section to operate the guard at the beginning of the movement of the table 2 or at any point in its movement thereafter. The guard may thus be immediately operated and held operated during substantially the entire movement of the table 2 or the guard may be held inoperative at the beginning of the movement of the table and then operated and held operated for the remainder of its movement.

For the purpose of vertically adjusting the entire guard between the movable table 2 and the fixed head 3 of the press, the supporting

member or upright 12 and its companion 24 are provided with spaced holes 32, 32 for the bolts 33, 33 to pass therethru and clamp the uprights to the head with the guard properly located relative to the danger zone between the dies in the press.

In presses where the table 2 is stationary and the head 3 is moved by the ram, the mounting of the guard is simply reversed by fastening the supporting member 12 to the stationary table and the bracket 29 with its cam rod 27 to the movable head.

Of course the safety guard shown and described may be changed, and variations may be required under certain conditions, therefore, while some of the constructional details are deemed preferable and I have shown and described them specifically, it is to be understood that I do not limit myself to such precise construction, but consider that I am at liberty to make such changes and alterations as fairly come within the scope of the appended claims.

I claim:

1. A safety guard comprising a series of levers pivotally held together in pairs and hingedly connected to form an expansible and contractible gate, fixed pivotal supporting means for the free end of one of the pair of levers at one end of the gate, movable supporting means for the free end of the other lever of the said pair of levers of the said end of the gate, an arm extension on said lever end held supported on said fixed pivotal supporting means, a movable cam rod engaging said arm extension and means for adjustably holding said cam rod for the operation of said arm extension.

2. A safety guard comprising a series of levers pivotally held together in pairs and hingedly connected to form an expansible and contractible gate, fixed pivotal supporting means for the free end of one of the pair of levers at one end of the gate, movable supporting means for the free end of the other lever of the said pair of levers of the said end of the gate, an arm extension on said lever end held supported on said fixed pivotal supporting means, a longitudinally movable cam rod, straight sections forming the upper and lower portions of said rod, an angular section intermediate the upper and lower straight sections so as to offset one straight section from the other and means carried by said arm extension for engagement by said cam rod to have the cam rod hold said arm extension in an inoperative position during part of its movement, operate said arm during another part of its movement and hold the arm in an operated position during the remainder of its movement.

3. A safety guard as set forth in claim 2 including means for adjustably holding said cam rod for permitting change of the movement of said arm extension by said cam rod.

4. A safety guard as set forth in claim 1 including supporting blocks carried by the ends of the levers of the pair of levers at the free end of the gate, a guard arm held fixed in one of said supporting blocks and movable in the other of said supporting blocks, and fixed guide means for guiding said guard arm in its movement by said gate.

5. A safety guard for machines having a movable member, and a bed plate below the movable member, said guard comprising a supporting member adapted for mounting on a fixed portion of the machine, a series of levers pivotally held together in pairs and hingedly connected to

form an expansible and contractible gate, means for pivotally supporting the free end of one of the pair of levers at one end of the gate to said supporting member, a link mounted to swing on said supporting member and pivotally connected to the end of the other lever of the said pair of levers at the end of the gate, a stop on said supporting member for engagement by said link when the gate formed by the series of levers is in a predetermined expanded position; a pair of parallel guide members carried by said supporting member, a guard arm carried by the ends of the levers of the pair of levers at the opposite

end of the gate, said guard arm projecting between said guide members so as to guide said guard arm and said levers.

5 6. A safety guard as set forth in claim 5 including an extension arm on the lever pivotally supported on said supporting member, a bracket swiveled on said extension arm, a cam rod movable thru said bracket, and means for adjustably holding said cam rod on the movable operating member of the machine to move therewith and cause said cam rod to operate said gate on the movement of said movable operating member.
